SAFETY MECHANISM FOR HANGING SCAFFOLDS

Ferdinand Puttre, 69—50 64th St., Glendale, N.Y.

Filed Apr. 1, 1957, Ser. No. 649,881

1 Claim. (Cl. 188—65.1)

This invention relates to a safety mechanism for hanging scaffolds.

The object of this invention is the provision of a safety device which may be used in conjunction with hanging scaffolds to prevent them from falling when the ropes which suspend them happen to break. Reference is here made particularly to scaffolds used by house painters. These scaffolds are suspended by ropes from hooks or other supports which are secured to the roof of a building. It has happened that ropes used for this purpose have given way while in use, causing injury and even death to those using the scaffold at the time. It has also happened that persons using such scaffolds have lost control of these ropes while operating them during ascent or descent of the scaffolds, with the same serious consequences.

The present invention provides safety means operating independently of the ropes from which the scaffolds are suspended. In the operation of this safety means, it is immaterial whether the ropes from which the scaffolds are suspended fail in use or whether they simply pull out of the control of those attempting to operate them. In either of these cases, an auxiliary supporting means automatically takes over and supports the scaffolds without any conscious or active participation on the part of those who are using the scaffolds.

More specifically, two auxiliary ropes or cables are provided, one at each end of a typical scaffold, the two ropes being supported at their upper ends from the roof of a building, and being engaged by a pair of stop members on the scaffold. These stop members prevent downward movement of the scaffold relative to the ropes except when the stop members are disengaged from the ropes by the persons on the scaffold. The moment the stop members are released, they automatically re-engage the ropes and further downward movement of the scaffold relative to said ropes is prevented.

The stop members to which reference has just been made are eccentric jam elements which become jammed or wedged into certain unyielding positions upon downward movement of the scaffold relative to the ropes. In these positions, they prevent further downward movement of the scaffold. The only way to terminate this jamming or wedging action is to disengage these stop members from the ropes and this can only be done by a deliberate effort by those who are on the scaffold.

The principles of this invention may be applied to various mechanisms, all of them encompassed within the scope of this invention. The drawing merely illustrates two such applications and it will be understood that this is not intended as a limitation of the scope and coverage of this invention.

In one illustrated form of the invention, the stop members are eccentric discs which engage the ropes and jam them against fixed arcuate supports. The eccentric discs are movable into and out of engagement with the ropes. In another illustrated form of the invention, the stop

2

members are a pair of wedges which ride against inclined planes into and out of engagement with the ropes.

The term "rope" as used herein is intended to include ropes, cables, chains and the like.

5 The invention is illustrated in the accompanying drawing in which:

Fig. 1 is a fragmentary front view of a scaffold which is adapted to be suspended or hung by ropes from the roof of a building and which is provided with a safety device made in accordance with one form of this invention.

Fig. 2 is an end view thereof.

Fig. 3 is a fragmentary view of another scaffold of like nature showing a safety device incorporated therein and made in accordance with a second form of this invention.

Scaffold 10 shown in the drawing is intended to represent any conventional scaffold suspended by ropes from the roof of a building and used by house painters, sign painters and other workers who engage in construction work or maintenance or repairs on the outside of buildings which are too tall to be serviced by ladders. The scaffold is supported at its ends by a strong metal hanger or frame 12. This hanger or frame serves as a saddle for the scaffold and at its upper end it is connected by means of a hook 14 or the like to a tackle block or pulley 16. Said tackle block is connected by means of rope 18 to a hook-shaped member 20 and a second tackle block 22, said hook-shaped member being adapted to be hooked to the roof of a building. The foregoing is all conventional. Secured to the scaffold is the safety mechanism herein claimed.

Mounted on the scaffold at each end thereof is a pair of uprights 30 and 32 respectively. These uprights should possess considerable structural strength and should be strongly secured to the scaffold. The securing means may be conventional and may consist of the usual nuts and bolts and braces. It will be observed that these uprights 30 and 32 are positioned on opposite sides 35 of a rope 34. The rope is supported at its upper end from a hook-shaped member 21 corresponding to hook 20 which supports ropes 18. Rotatably mounted on upright 32 by means of pin 36 is an eccentric 38. This eccentric may simply be a disc which is mounted off-center for angular movement about pin 36.

Opposite eccentric 38 is the upright 30 and it will be noted that an arcuate cutout 40 is provided in said upright to receive the eccentric 38. It will also be noted that rope 34 rides upon eccentric 38 between said eccentric and the arcuate portion of upright 30 along its arcuate cutout 40. A spring 42 is connected at one end to upright 30 and at its opposite end to eccentric 38 and its action is to pull the eccentric in clockwise direction as viewed in Fig. 1. This would tend to bring the eccentric into engagement with the rope and to jam it against the arcuate portion of upright 30.

A lever 44 is secured to eccentric 38 by means of pin 36 and a second pin 37. A weight 46 is provided on lever 44 and said weight tends to swing the lever downwardly about the axis of pin 36 and this has the effect of urging eccentric 38 to move in clockwise direction, precisely as it is caused to move under the influence of spring 42. Either the spring alone or the weight alone would normally suffice for this purpose but the two are provided as an added safety precaution.

A pad 50 is secured to the scaffold 10 adjacent each upright 32. Pivotal mounted on said pad is a pedal 52. A cable 54 is secured at one end to said pedal and at its opposite end to the lever 44. Intermediate its ends, the cable 54 rides on a pulley 56 which is rotatably mounted on upright 32 above lever 44. The pedal may be de-

pressed to pull cable 54 and thereby to cause the lever 44 to swing in counter-clockwise direction, as viewed in Fig. 1, about the axis of pin 36. Since the lever is secured to eccentric 38, this causes the eccentric to swing in counterclockwise direction out of engagement with the rope 34. This action takes place against the influence of spring 42 and weight 46 and it frees the scaffold for movement relative to the rope 34. When the pedal 52 is released, spring 42 and weight 46 will automatically swing the eccentric in clockwise direction back into engagement with the rope, thereby jamming the rope between the eccentric and the arcuate portion of upright 30 and preventing movement of the scaffold relative to said rope 34.

Referring now to the second form of this invention and to Fig. 3, it will be understood that scaffold 60 in Fig. 3 is intended to correspond to scaffold 20 in Fig. 1 and to represent a conventional scaffold. At each end of scaffold 60 is the conventional supporting means for supporting it from the roof of a building but this is not shown in the drawing both for the reason that it is conventional and for the further reason that showing it would tend to confuse the disclosure of the inventive features of the invention.

At each end of scaffold 60 is an upright 62 and a second upright 64. These two uprights are securely fastened to the scaffold and it will be noted that they are spaced apart to accommodate a rope 66 between them. This rope 66 corresponds to rope 34 above mentioned and it is the auxiliary or safety rope which is designed to support the scaffold upon failure of the conventional supporting means.

There is a cutout 68 in upright 64 and along said cutout is a diagonal wall 70 which serves in the present invention as an inclined plane. Slidably supported in the cutout 68, against the inclined plane 70 is a wedge 72. A spring 74 is connected at one end to the top of said upright 64 and at its opposite end to the wedge 72 and it tends to urge the wedge upwardly along said inclined plane 70. It will be observed that this upward movement of the wedge against the inclined plane brings it into engagement with rope 66 and jams the rope against upright 62. This locks the scaffold against movement relative to said rope.

A pad 80 is secured to scaffold 60 at each end thereof. A pedal 82 is pivotally supported on said pad. A cable 84 is connected at one end to pedal 82 and at its opposite end to a lever 86. This lever is pivotally supported on upright 64 by means of pin 88. At one end of lever 86 is a bar 90 which is pivotally secured at its lower end to said lever 86 and at its upper end to wedge 72. A weight 92 is secured to lever 86 at the opposite end of said lever from bar 90. It will now be understood that the action of weight 92 is to swing lever 86 in clockwise direction as viewed in Fig. 3. This movement causes the bar 90 to move upwardly and to push the wedge 72 upwardly along the inclined plane 70. It is therefore clear that weight 92 and spring 74 both perform the same function with respect to wedge 72; and that is to move the wedge upwardly along the inclined plane into jamming engagement with the rope 66.

When it is desired to release wedge 72 from rope 66, pedal 82 is depressed. It will now be noted that cable 84 rides on pulley 96 which is supported on upright 64. Since one end of the cable is secured to the pedal 82 and the opposite end is secured to lever 86, depressing the pedal will cause the cable 84 to pull lever 86 in counter-clockwise direction as viewed in Fig. 3. Since said lever is connected to wedge 72 by means of bar 90, the effect of this counter-clockwise movement of the lever would

be to pull the wedge down along the inclined plane 70 and out of engagement with rope 66. This would be done against the action of spring 74 and weight 92 and the result would be to free the scaffold for movement relative to the rope 66. When it is desired to re-engage the rope and to prevent such relative movement between the scaffold and the rope, pedal 82 is released and spring 74 and weight 92 will act upon the wedge to move it upwardly into jamming engagement against the rope. Small ridges 98 may be formed on the side of upright 62 which faces rope 66 directly opposite the wedge 72 and corresponding ridges 99 may be formed on that side of the wedge which also faces the rope. These ridges serve to increase the frictional engagement between the wedge 72 and upright 62 on the one hand and the rope 66 on the other.

The foregoing is illustrative of preferred forms of this invention and it will be understood that the preferred forms may be modified and other forms may be provided within the broad spirit of the invention and the broad scope of the claim.

I claim:

A brake device for rope-suspended scaffolds and the like, comprising a pair of uprights, said pair of uprights being spaced apart to receive a rope between them, and wedging means on the first of said pair of uprights adapted to engage and wedge the rope against the second of said pair of uprights, release means being provided in connection with said wedging means to disengage said wedging means from the rope, said first upright being provided with a sloping surface facing the rope, said sloping surface being adapted to function as an inclined plane, the wedging means comprising a wedge having one edge sliding on the inclined plane surface of said first upright and the other edge facing the rope, being parallel to the rope and engaging the same, said wedge being movable in one direction to jam the rope against said second upright and movable in the opposite direction out of jamming engagement with said rope, a spring being connected between the wedge and said first upright to urge the wedge into jamming engagement with the rope, a pivoted lever being also provided on said first upright and a link between one end of said lever and the wedge, a weight being provided at the opposite end of said lever and acting to swing the lever in such direction as to cause the link to urge the wedge into jamming engagement with the rope, thereby complementing the acting of said spring, said release means comprising a pedal, a pulley being provided on said first upright and a cable extending around said pulley, said cable being connected at one end to the pedal and at the opposite end to the lever, whereby depressing the pedal causes the cable to pull upon the lever and to swing the lever in the opposite direction from the direction in which it is urged by the spring and weight, thereby withdrawing the wedge from jamming engagement with the rope.
